LIGHTING FIXTURE PANEL

Elmer Szantay, Chicago, Ill.

Application March 18, 1959, Serial No. 55,045

Term of patent 14 years

(Cl. D48—16)

Fig. 1 is a perspective view of a lighting fixture panel showing my new design as seen from the top thereof.

Fig. 2 is a perspective view thereof as seen from the bottom.

Fig. 3 is an enlarged bottom plan view of a portion thereof.

Fig. 4 is an enlarged fragmentary sectional view thereof taken substantially along the line 4-4 of Fig. 3.

Fig. 5 is a further enlarged fragmentary sectional view through a portion of the center part of the panel and taken substantially along the line 5-5 of Fig. 6.

Fig. 6 is a bottom plan view of the portion of the panel illustrated in Fig. 5.

Fig. 7 is a vertical sectional view as taken along the line 7-7 of Fig. 6.

I claim:

The ornamental design for a lighting fixture panel, substantially as shown.
